[57] **CLAIM**

The ornamental design for a shoe with removable heel, as shown and described.

DESCRIPTION

FIG. 1 is a bottom, perspective view of a shoe with removable heel showing my new design;
FIG. 2 is a top plan view thereof;
FIG. 3 is a front elevational view thereof;
FIG. 4 is a rear elevational view thereof;
FIG. 5 is a right side elevational view with the removable heel in place, the left side being a mirror image thereof; and,
FIG. 6 is a bottom plan view with the heel separated from the shoe.
